[57] CLAIM

The ornamental design for a retractable knife, as shown
and described.

DESCRIPTION

FIG. 1 is a perspective view of my retractable knife;
FIG. 2 is an elevational view of one side of the retract-
able knife, the other side being substantially identical
thereto;

FIG. 3 is a top plan view of the device shown in FIGS.
1 and 2;

FIG. 4 is an elevational view of one end of the device;
FIG. 5 is an elevational view of the opposite end
thereof; and

FIG. 6 is a perspective view of the invention with the
knife blade retracted.
